UNITED STATES PATENT OFFICE

WILLIAM CAMPBELL WHYTE, OF ELYRIA, OHIO, ASSIGNOR TO THE ELECTRO-ALLOYS COMPANY, OF ELYRIA, OHIO, A CORPORATION OF OHIO

RETOUR

Application filed January 9, 1930. Serial No. 419,535.

My invention relates to retorts, and relates particularly to rotatable retorts of a type, especially for use in case-hardening or annealing small iron or steel articles deposited therein in bulk.

My invention pertains generally to the general type of apparatus disclosed in U. S. Letters Patents 822,460, 847,588, 884,180, 884,181, wherein steel or other articles to be case-hardened are deposited in a continuously rotated retort, wherein the articles are agitated, while exposed to a current of carburizing gas, directed therethrough.

My invention, however, is susceptible of a broader application than for case-hardening, and is especially adaptable for all purposes where the articles are to be brought to a relatively high heat under conditions whereby rapid discharging and recharging of the heated retort is a desideratum.

Considerable difficulty has previously been had in retorts of the above character so formed as to efficiently agitate the articles deposited therein, when used under alternate conditions of high and low temperatures.

Efforts have been to effect a more efficient agitation of the articles contained in such retorts by providing the interior wall thereof with inner longitudinally extending ribs, but such retorts have been found objectionable since due to the variation in expansive and contractive stresses set up in the material of the retort walls due to the temperature variations to which the retort is exposed, they crack and are otherwise injured.

An object of my invention is to provide a retort which resists destruction due to variations in heat, but which at the same time is very efficient in operation and in the agitation of articles placed therein, when the retort is rotated.

Another object of my invention is to provide a retort of improved form for operative purposes, which will not be subject to injury, because of heat changes during the process of manufacturing the retort, or to which it may be exposed in the practical use of the retort.

Another object of my invention is to provide an improved heat resistant rotatable carburizing retort.

Other objects of my invention and the invention itself will be better understood by reference to the following description of an embodiment of my invention, in which reference is had to the accompanying drawings illustrating the said embodiment.

Referring to the drawings:

Fig. 1 is a longitudinal medial sectional view of longitudinally aligned fragments of an embodiment of my invention.

Fig. 2 is an end view taken on the line 2—2 of Fig. 1.

Fig. 3 is a section taken on the line indicated at 3—3 of Fig. 2.

Fig. 4 is an end elevational view of the discharge end of the retort of the foregoing figures and of a supporting tubular furnace shown in operative association therewith, and of auxiliary apparatus including supporting rollers for the retort, and driving and supporting elements for the furnace.

Fig. 5 is a plan view of certain of the driving elements for the retort.

Fig. 6 is an elevational view of the machine taken from the end opposite to that of Fig. 4.

Fig. 7 is a longitudinal medial sectional view of an end fragment of the furnace, of the associated end of the retort and certain adjacent parts, some of the parts being shown in elevation.

Fig. 8 is a transverse section taken on the line 8—8 of Fig. 1.

Referring now to the different figures of drawings, in all of which like parts are designated by like reference characters, the retort, illustrated therein, embodying my invention, comprises an integral tubular casting preferably of a nickel-chrome alloy material, comprising an enlarged tubular barrel 11, a reduced tubular stem end 12, adapted to be rotatably supported by its ends, which are adapted for projection externally of the tubular tiltable furnace 18 according to a well known practice, upon supporting rolls 19 and 20. The barrel 11 is provided at an end with an annular flange 13 to which a cover, 35, may be clamped in the usual manner.

The relative disposition of the retort, the tubular furnace, the supporting rolls for the retort, and the means for rotating the retort

may be susceptible to considerable variation in practice, and do not form a part of the present invention, being well known instrumentalities susceptible of use in combination with retorts of the general class in which my 5 improved retort is contained.

Generally, however, the retort is telescoped within the tubular furnace 18 and projects beyond the two ends thereof, by the reduced portion 12 projecting beyond the head 14 at 10 one end of the furnace and by the portion 15 which project beyond the head 16 at the other end of the furnace.

The furnace preferably comprises its said 15 end heads, and the cylindrical barrel 10 joining the heads, there being provided a refractory lining 18 of fire-brick, or the like, for said barrel and heads, as well as suitable burners for introducing gas to the space, between the interior lining of the furnace and 20 the retort, forming the flame chamber of the furnace.

The retort is rotatably supported by its 25 ends 12 and 15 upon separate pairs of rollers 20 and 19 respectively. The rollers 19 disposed at one end of the furnace, to support the end 15 of the retort, engage the outer surface of the enlarged end 15, at points normally disposed below the horizontal 30 plane including the axis of the retort.

The rollers 20 engage the stem 12 between spaced flanges 21 of a wheel 22 which is rigidly secured on to said stem, at points, also disposed below the horizontal plane of the 35 axis of the retort; the wheel 22 is provided also with a set of sprocket teeth 23 disposed peripherally of the wheel 22 which are embraced by a driving chain 24, is driven by a sprocket wheel 25 which receives power from 40 any suitable source, through such instrumentalities as are shown generally in Figure 5 at 40.

The tubular furnace is suspended intermediate its heads 12 and 13 by means of 45 trunnions 26 extending from laterally projecting portions 27 of the tubular furnace and which trunnions are mounted in opposite disposed bearings 28 of fixed standards 29 which support the mechanism.

50 Suitable means such as the hand wheel 30, acting through a worm 41 and gearsector 42 serve to bodily tilt the entire furnace with its continuously rotating retort about the axis of the trunnions, whereby the rotatable retort 55 may have its discharge end 15 turned downwards to discharge articles heat-treated and/or carburized therein, or whereby the retort may assume its alternative horizontal operative position as illustrated, wherein the rotating retort is exposed to the heat of combustion in the flame chamber from without its walls.

Carburizing gas is introduced in the usual 65 manner through the reduced end 12 of the retort by an axially projecting inlet tube 31,

receiving gas from a conduit 32 and which is joined to the reduced end 12 of the retort by a coupling element 33. A cover 35 is secured by clamps 36 to the flanged end of the retort and a venting tube 34 is projected through 70 said cover and supported thereby and performs the dual functions of venting vitiated carburizing gas from the retort, as well as to facilitate the removal of the cover.

A coupling 34 joins the conduit 32 to the inlet tube 31, said inlet tube being, however, preferably rotatable within the coupling and laterally apertured to receive carburizing gas from the pipe 32, there being preferably 80 provided suitable packing to prevent loss of gas from the coupling. The retort of my invention comprises intermediate its enlarged end 15 and its reduced opposite stem end 12 a carburizing and/or heat treating chamber portion 35 whose tubular walls are 85 corrugated to form a plurality of longitudinally extending integral folds, forming alternate longitudinally extending ridges and depressions for substantially the full length of the chamber. In the embodiment illustrated as best shown in Fig. 2, there are four of these ridges, shown at 36, which are of considerable width, extending radially of the axis of the chamber, with relatively narrow depressions 37 interposed between them and formed by inwardly extending folds 38 comprising the lateral walls of the ridges.

The corrugated tube thus formed provides a plurality of longitudinally extending baffles 90 on its inner surface comprising the lateral walls of the inward folds which engage with the articles placed in the chamber during rotation of the retort to tumble them in a most efficient manner, so as to expose all sides of the article to the action of the carburizing 100 gas passed into the retort.

The material of the folds 38 and the end wall 39 are bridged, near the end of the chamber 35, interiorly thereof, by integral webs 40, which also effect a baffle function and strengthen the structure at this point. Exterior webs 41 also bridge the reduced stem end 12 of the retort and the end portions of the outwardly extending ridges 36.

I find that a retort constructed as above described having walls consisting of a plurality of alternate inward and outward folds, will absorb the stresses due to alternate contraction and expansion induced by thermo- 110 alternate opposite thermal changes as during making the casting to form the retort and during the subsequent practical use of the retort.

Having thus described my invention in a 115 specific embodiment, I am aware that numerous and extensive departures from the embodiment herein illustrated and described may be made, but without departing from the spirit of my invention.

I claim:

1. A rotatable retort of the class described comprising a tubular heat treating chamber, and a reduced stem portion integrally secured thereto by an end wall to align the same therewith, the chamber having a longitudinally extending tubular wall formed with longitudinally extending corrugations, the corrugations being deflected bodily inwardly from the intermediate portions of the wall, and the end wall having inwardly generally radially extending recesses aligned with the outer wall of the corrugations.
2. A rotatable retort of the class described comprising a tubular heat treating chamber, and a reduced stem portion integrally secured thereto by an end wall to align the same therewith, the chamber having a longitudinally extending tubular wall formed with longitudinally extending corrugations, the corrugations being deflected bodily inwardly from the intermediate portions of the wall, and the end wall having inwardly generally radially extending recesses aligned with the outer wall of the corrugations, and webs disposed within said chamber integrally joining the inner end portions of the inwardly projecting corrugations with inwardly disposed portions of said end wall.
3. A rotatable retort of the class described comprising a tubular heat treating chamber, and a reduced stem portion integrally secured thereto by an end wall to align the same therewith, the chamber having a longitudinally extending tubular wall formed with longitudinally extending corrugations, the corrugations being deflected bodily inwardly from the intermediate portions of the wall, and the end wall having inwardly generally radially extending recesses aligned with the outer wall of the corrugations, and webs, externally of the tubular chamber, connecting the stem and the end wall at portions thereof between said recesses.
4. A rotatable retort of the class described comprising a tubular heat treating chamber, and a reduced stem integrally secured thereto by an end wall to longitudinally align the stem therewith, the chamber having a longitudinally extending tubular wall formed with longitudinally extending corrugations, the corrugations being deflected bodily inwardly from the intermediate portions of the wall, webs disposed within said chamber integrally joining the inner end portions of the inwardly projecting corrugations with inwardly disposed portions of said end wall, and webs disposed externally of the tubular chamber connecting the stem and the end wall at portions thereof between said corrugations.

In testimony whereof I hereunto affix my signature this thirty-first day of December, 1929.

WILLIAM CAMPBELL WHYTE.
